UNITED STATES PATENT OFFICE.

WILLIAM SNOBBLE, OF SOUTH HAVEN, MICHIGAN.

POTATO-BUG DESTROYER.

SPECIFICATION forming part of Letters Patent No. 461,551, dated October 20, 1891.

Application filed February 3, 1891. Serial No. 379,982. (No model.)

To all whom it may concern:

Be it known that I, WILLIAM SNOBBLE, a citizen of the United States, residing at South Haven, county of Van Buren, State of Michigan, have invented a new and useful Potato-Bug Destroyer, of which the following is a specification.

This invention relates to machines provided with an endless traveling apron and means for gathering the bugs onto forward portion of said apron, said apron traveling between two rollers, which crush the bugs.

In the drawings forming part of this specification, Figure 1 is a plan view; Fig. 2, a side elevation; Fig. 3, a rear elevation, parts being in section on line 55 in Fig. 1; and Fig. 4 is a detail of lettered parts below described.

Referring to the lettered parts of the drawings, A represents a wheeled frame, to which 20 the tongue or thills is attached for drawing the machine. Below this frame is another frame B, which can be raised and lowered at will by the ordinary lever arrangement N e. The front end of this frame is substantially 25 level, while the rear portion is at an upward incline. At or near the center of said frame are two rollers L M, one above another.

In the front end of the frame B is a shaft E', and the rear end of said frame is provided 30 with a shaft E, and these two shafts carry the endless apron D, the upper part passing between the rollers L M and the lower part of said apron passing beneath the roller M.

Mounted upon the rear end of the frame A 35 is a transverse shaft provided at one end with a gear H and a sprocket-wheel G. The hub of one of the wheels is provided with a sprocket-wheel F. Motion is transmitted from the sprocket-wheel F to the sprocket-40 wheel G by means of sprocket-chain J. The shafts E E' are gear-connected by gears H I, Fig. 3. The opposite ends of the shafts E E' are connected by sprocket wheels and chains

K, as in Fig. 1. By this means motion is imparted to the shafts when the machine is in 45 operation, thus causing the endless belt to travel around the end shafts and between the rollers L M. The bug-gatherers consist of arms C, radiating from an upright axis, as in Figs. 1 and 2, said arms being arranged 50 over the apron and in position to engage the tops of the potato-vines and sweep the bugs onto said apron. The axles of the gatherers C are connected with shaft E' at each end by beveled gears S, as in Figs. 2 and 4. Thus 55 when motion is imparted to the machine the bugs which are swept onto the front end of the apron D will be carried back between the rollers L M, where they are crushed, and are thence carried and deposited over the rear end 60 of the machine. If found necessary, a suitable scraper may be employed for freeing the apron from the crushed bugs.

Having thus described my invention, what I claim as new, and desire to secure by Letters Patent of the United States, is—

The combination of the wheeled frame and a supplemental frame beneath the wheeled frame and suspended therefrom, a shaft in the front and rear end of the supplemental 70 frame, an endless belt carried by said shafts, two rollers mounted in the supplemental frame, between which rollers the upper part of the endless belt travels, gatherer-arms radiating from upright axles in the supplemental frame and gear connected with the forward shaft of said frame, and the sprocket 75 wheels and chains for driving the shafts of said frame, substantially as set forth.

In testimony of the foregoing I have hereunto 80 subscribed my name in the presence of two witnesses.

WILLIAM SNOBBLE.
